(57) **CLAIM**

The ornamental design for a combined inflation machine and turntable assembly, as shown and described.

DESCRIPTION

FIG. 1 is a top isometric view of a combined inflation machine and turntable assembly, showing our new design; FIG. 2 is a bottom isometric view of the combined inflation machine and turntable assembly of FIG. 1;

FIG. 3 is a right side view of the combined inflation machine and turntable assembly of FIG. 1;

FIG. 4 is a left side view of the combined inflation machine and turntable assembly of FIG. 1;

FIG. 5 is a front view of the combined inflation machine and turntable assembly of FIG. 1;

FIG. 6 is a rear view of the combined inflation machine and turntable assembly of FIG. 1;

FIG. 7 is a top plan view of the combined inflation machine and turntable assembly of FIG. 1;

FIG. 8 is a bottom plan view of the combined inflation machine and turntable assembly of FIG. 1;

FIG. 9 is a top isometric view of the turntable, shown separately for ease of illustration;

FIG. 10 is a left side view of the turntable of FIG. 9;

FIG. 11 is a front side view of the turntable of FIG. 9;

FIG. 12 is a right side view of the turntable of FIG. 9;

FIG. 13 is a rear side view of the turntable of FIG. 9;

FIG. 14 is a top plan view of the turntable of FIG. 9; and,

FIG. 15 is a bottom plan view of the turntable of FIG. 9. Any portions of the Figures shown in broken lines are not part of the claimed design but are for illustration only.
